AUTOPPOINT COMPANY, OF CHICAGO, ILLINOIS, A CORPORATION OF ILLINOIS

FOUNTAIN PEN

Application filed June 4, 1928. Serial No. 282,744.

Our invention relates to fountain pens and more particularly to a novel pressure bar construction therefor and is an improvement over our prior co-pending application Serial 5 No. 287,756, filed December 5, 1927.

An object of our invention is to provide a fountain pen having the pressure bar and associated mechanism of such arrangement and construction as to avoid the common objections now present. The user of fountain pens frequently finds a blot on his paper as the result of moving the pen too rapidly above the paper, or setting the pen down roughly. The leakage of pens in this way is generally 10 caused by reason of the weight of the pressure bar mechanism on the ink sack. Obviously slight movement of the pen will impart a momentum to the most fragile pressure bar, with the aforementioned result. An 15 object therefore, of our invention is to so lock the entire pressure bar mechanism that such annoyances will be avoided.

A further object of our invention is to provide a pressure mechanism that will, at all 20 times, compress the ink sack to its fullest extent, so that, regardless of the age of the pen, it will always contain the same amount of 25 ink.

A further object of our invention is to 30 eliminate the unsightly pressure bar lever from the side of the barrel. Pressure bar levers so located are very apt to become loose, and if caught, will open and discharge the contents of the pen. A further objection to 35 such a practice, is that the opening provided for the filling lever frequently is of such a size as to admit foreign matter and dust, resulting in added friction and injury to the sack within the barrel.

40 These and other objects will appear by a study of the following description of the drawings, in which—

Fig. 1 is a view, partly in section showing a fountain pen constructed in accordance 45 with our invention;

Fig. 2 is a view at right angles to that of Fig. 1, partly in section;

Fig. 3 is a sectional view showing the ink 50 sack compressed;

Fig. 4 is a plan view of the pressure bar and associated parts;

Fig. 5 is a longitudinal sectional view of the pressure bar and associated parts;

Fig. 6 is a cross sectional view taken on 55 the line 6—6 of Fig. 3;

Fig. 7 is a sectional end view taken on the line 7—7 of Fig. 1.

By referring to the drawings, it will be seen that we have provided a barrel 10, compressible ink sack 11, plug 12, pen 13 and hood 14.

Located within the barrel is the sack compressing means, including the channel shaped pressure bar 15, short fulcrum lever 16, pivoted to the pressure bar at some suitable point as at 17. Pivoted to the lever 16 at 16^a is the link 18 of suitable length. The link 18 and pressure bar 15 are both pivotally secured at 15^a and 18^a to the bellcrank 19 which is pivotally secured to the upper end of the pen 60 barrel by a pin 20. The pressure bar is slightly deformed at its upper end to bring the pivot 15^a below the plane thereof for a purpose later to be described. The screw 65 cap 21 is provided as a lock for the bellcrank 70 in closed position.

It is thus seen that the pressure bar and associated parts are secured to the barrel by only one pin, 20. Thus the entire movement of the mechanism is relative to the pin, 20.

The operation of the filling mechanism is better understood by a description in view 85 of the apparatus here disclosed: The apparatus is shown in locked position, closed, in Fig. 1. In this position the fulcrum lever and link lie in a continuous straight line, enclosed by the channels of the pressure bar. The pivot 15^a being below the channel leaves 90 the channel free to receive the link 18. The tighter the bellcrank is locked down, the farther up the pivot 15^a will be forced, thus forcing the pressure bar, fulcrum lever and link tight up against the barrel, thereby 95 avoiding any pressure against the sack in the handling.

When the sack is to be compressed, the cap 21 is removed and the bellcrank rocked upwards, thus pushing the link 18 forward. 100

This movement raises the fulcrum lever 16 which bears against the wall of the barrel for a short distance, thus forcing the pressure bar downward against the sack. When the bellcrank is pushed upwards to its limit, the fulcrum lever will have passed its center, and the sack will be kept down without holding the bellcrank, as shown in Fig. 3. To release the sack and permit the entrance of ink, 10 the bellcrank is simply pushed down, and locked by the cap 21.

Thus it is seen that we have provided a self-filling fountain pen having the pressure bar and associated mechanism tightly pressing 15 the barrel wall when the sack is filled, a simple fulcrum lever bar actuating means, and a simple and efficient operating means at the upper end of the pen, locked by the cap, and free from possibility of the entrance of 20 any foreign matter to disturb the inside of the barrel.

Obviously modification and variations may be made in the device here disclosed and we do not wish to be limited except as indicated in the appended claims.

We claim:

1. The combination with a pen barrel and ink sack of sack compressing means comprising a pressure bar, a floating fulcrum arm 30 having a connection to the lower end of the bar and a sliding contact with the inside of the barrel, a crank connected to the bar and pivoted to the barrel, a link connecting the crank and the fulcrum arm, and an operating 35 arm on the crank adapted to project outside of the end of the barrel.

2. The combination with a pen barrel and ink sack of sack compressing means comprising a pressure bar, a floating fulcrum arm 40 having a connection to the lower end of the bar and a sliding contact with the inside of the barrel, a crank connected to the bar and pivoted to the barrel at a point beyond the upper end of the ink sack, a link connecting the crank and the fulcrum arm, an operating arm on the crank adapted to project outside of the end of the barrel, and a screw 45 cap for locking said crank in closed position.

3. In a fountain pen, the combination with 50 a barrel, a cap, a pen and a collapsible ink sack in said barrel, of means for compressing said sack, said means comprising a pressure bar contacting said ink sack substantially the length thereof, a fulcrum lever secured 55 to said pressure bar between the ends thereof, a link connected to the free end of said fulcrum lever and a bellcrank, said bellcrank being pivoted to the end of said barrel and operatively connected to said pressure bar 60 and link.

4. In a fountain pen, the combination with 65 a barrel, a cap, a pen and a collapsible ink sack in said barrel, of means for compressing said sack, said means comprising a pressure 70 bar contacting said ink sack substantially the

length thereof, a fulcrum lever secured to said pressure bar between the ends thereof, a link connected to the free end of said fulcrum lever, a bellcrank, said bellcrank being pivoted to the end of said barrel and operatively connected to said pressure bar and link, and a screw cap for locking said bellcrank in closed position.

5. In a device of the class described, the combination of a pen barrel, a compressible ink sack therein, and means for compressing said sack, which consists of a pressure bar, a fulcrum lever attached thereto between the ends thereof, an operating link, connected to said fulcrum lever, at the free end thereof, and a bellcrank, said bellcrank being pivoted to the end of said barrel and operatively connected to said pressure bar and link, the free end of said fulcrum lever contacting the wall of said barrel as a bearing surface.

6. In a device of the class described the combination of a pen barrel being open at one end and adapted to receive a pen plug, and having a cross slot in the other end, a compressible ink sack disposed in said barrel, a pressure bar resting on said sack substantially the length thereof, a fulcrum lever, one end of which is secured to said pressure bar, and the free end of which is adapted to contact the wall of said barrel as a bearing surface, a link secured to said fulcrum lever between the ends thereof, and a bellcrank, said bellcrank being received in the slot in the closed end of said barrel and adapted to be supported on a pivot therein, and to have operative connection with said link and said pressure bar.

7. In a device of the class described the combination of a pen barrel being open at one end and adapted to receive a pen plug, and having a cross slot in the other end, a compressible ink sack disposed in said barrel, a pressure bar resting on said sack substantially the length thereof, a fulcrum lever, one end of which is secured to said pressure bar, and the free end of which is adapted to contact the wall of said barrel as a bearing surface, a link secured to said fulcrum lever between the ends thereof, and a bellcrank, said bellcrank being received in the slot in the closed end of said barrel and adapted to be supported on a pivot therein, and to have operative connection with said link and said pressure bar, said bellcrank being operable from the outside of said barrel.

8. In a device of the class described the combination of a pen barrel being open at one end and adapted to receive a pen plug, and having a cross slot in the other end, a compressible ink sack disposed in said barrel, a pressure bar resting on said sack substantially the length thereof, a fulcrum lever, one end of which is secured to said pressure bar, and the free end of which is adapted to contact the wall of said barrel as a bearing surface, a

link secured to said fulcrum lever between the ends thereof, a bellcrank, said bellcrank being received in the slot in the closed end of said barrel and adapted to be supported on a pivot therein, and to have operative connection with said link and said pressure bar, said bellcrank being operable from the outside of said barrel, and a screw cap adapted to lock said bellcrank in a closed position.

9. In combination, a barrel having an open upper end, and ink sack, a pressure bar, a floating lever connected at one end to the pressure bar, and having a sliding fulcrum on the inside of the barrel, a bellcrank pivoted in said open end of the barrel, and having an operating arm projecting beyond said open end, said pressure bar being pivoted to one arm of said bell crank, and a link connecting the fulcrum end of said floating lever to the other arm of the bell crank, the bell crank being so positioned that the pivot points of the link and bar on the bell crank arms are substantially in line with each other and with the longitudinal axis of the barrel when the sack is in inflated position, whereby on oscillation of the bell crank, the link is caused to travel a substantial distance longitudinally of the barrel and the bar only a relatively short distance longitudinally.

30. In testimony whereof we have affixed our signatures.
